UNITED STATES PATENT OFFICE.

EDWARD K. ROLLINS, OF SCRANTON, PENNSYLVANIA, ASSIGNOR TO HUNT BROTHERS & COMPANY, (LIMITED,) OF SAME PLACE.

MINER'S LAMP.

SPECIFICATION forming part of Letters Patent No. 279,503, dated June 12, 1883.

Application filed March 20, 1882. (No model.)

To all whom it may concern:

Be it known that I, EDWARD K. ROLLINS, of Scranton, in the county of Lackawanna, and State of Pennsylvania, have invented certain 5 Improvements in Miners' Lamps, of which the following specification is a description.

This invention relates to improvements in miners' lamps, the invention consisting in making the spout and cylindrical portion or 10 body of the lamp out of one piece of metal stamped or otherwise formed up to the desired size and shape, and having a separate bottom and breast attached thereto, as by soldering, all as hereinafter specifically set forth and 15 claimed.

In the accompanying drawings, Figure 1 is a side view of a miner's lamp embodying my improvements. Fig. 2 is a central longitudinal section thereof; and Fig. 3 is a perspective 20 view of my combined cylinder and spout.

Similar letters of reference indicate corresponding parts in all the figures.

A designates the cylindrical portion or body of the lamp, having its spout B made of the 25 same piece of metal. This cylindrical portion A is provided at its upper end with a breast, C, having a wide mouth or opening, into which a stopper or cap, D, is arranged to fit snugly to close the opening. The lower end of the 30 cylindrical portion A fits into a bottom, E, which may be soldered or otherwise secured thereto. The cylindrical portion A and its spout B are stamped up out of one piece of metal, and the edges a a' and b b' are over- 35 lapped and soldered or sweated or otherwise securely connected to make a fluid-tight joint.

A miner's lamp made in accordance with my invention possesses the following advantages over the old form: First, the spout and body being without connecting joints, there is 40 entire absence of the dripping of the oil that has heretofore been a source of annoyance and discomfort to miners; second, miners' lamps are exposed to hard usage, and are bent and battered to such an extent as to start the 45 seams in the old forms, producing leakage and rendering the lamp practically useless. I avoid the leakage and the other evils resulting from damage to the lamp by discarding seams, and making the lamp-body and its most 50 exposed part (the spout) in one piece.

I am aware that coal-hods and some other vessels have been made with the mouth and body in one piece, but I am not aware of the prior existence of a miner's lamp made as 55 herein shown and described.

What I claim as my invention, and desire to secure by Letters Patent, is—

1. A miner's lamp having its spout B and the body A formed together as one piece without uniting seams, substantially as shown and described. 60
2. The combination, substantially as shown and described, of the body A, seamed at a a', and the spout B, seamed at b b', the two being 65 made of one piece without connecting-seams, with the bottom E, breast C, and cap D, as and for the purpose specified.

EDWARD K. ROLLINS.
